Primary Examiner — Ricky Pham(74) *Attorney, Agent, or Firm* — Foley Hoag LLP; Dana M. Gordon; Stephen J. Kenny(57) **CLAIM**

The ornamental design for a sausage cutter, as shown and described.

DESCRIPTION

FIG. 1 is a perspective view of a sausage cutter showing our new design;

FIG. 2 is another perspective view thereof;

FIG. 3 is a left side view thereof;

FIG. 4 is a right side view thereof;

FIG. 5 is a top view thereof;

FIG. 6 is a bottom view thereof; and,

FIG. 7 is a front view thereof.

The broken lines shown are included for the purpose of illustrating the unclaimed portions of the sausage cutter and form no part of the claimed design.

1 Claim, 5 Drawing Sheets(56)
